(57) **CLAIM**

The ornamental design for a multiple roll and boxed good cabinet dispenser, as shown and described.

DESCRIPTION

FIG. 1 is a top, front, and right side perspective view of a multiple roll and boxed good cabinet dispenser showing my new design;

FIG. 2 is a front elevational view thereof;

FIG. 3 is an enlarged left side elevational view thereof;

FIG. 4 is an enlarged right side elevational view thereof;

FIG. 5 is a top plan view thereof,

FIG. 6 is a bottom plan view thereof; and,

FIG. 7 is a bottom, rear, and right side perspective view thereof.

The broken-line disclosure of rolled goods in the views is for illustrative purposes only and forms no part of the claimed design.
